FEEDING MECHANISM FOR SEWING MACHINES

John D. Karle, Roselle Park, N. J., assignor to The Singer Manufacturing Company, Elizabeth, N. J., a corporation of New Jersey

Application October 25, 1941, Serial No. 416,437

5 Claims. (Cl. 112—215)

This invention relates to sewing machines and more particularly to a feeding mechanism therefor.

An object of this invention is to provide an improved form of feeding mechanism which is simple in construction and which is capable of keeping the feed-dog in a substantially horizontal position while it is feeding the work so that all of the feed-dog teeth will uniformly feed the work.

With the above and other objects in view, as will hereinafter appear, the invention comprises the arrangements of parts hereinafter set forth and illustrated in the accompanying drawings of a preferred embodiment of the invention, from which the several features of the invention and the advantages attained thereby will be readily understood by those skilled in the art.

In the accompanying drawings,

Fig. 1 is a side elevation, partly in section, of a sewing machine having my improved feeding mechanism embodied therein.

Fig. 2 is a bottom plan view to disclose the mechanism beneath the bed.

Fig. 3 is an end elevation of the machine looking from the left of Fig. 1.

Fig. 4 is a diagrammatic view of the feed-actuating eccentrics disclosing their phase relation.

Fig. 5 is an enlarged fragmentary view of the feed-bar.

In the embodiment of the invention selected for illustration, 10 is the sewing machine bed to which is secured the overhanging frame or gooseneck 11 which terminates in a hollow head 12. Journaled in the spaced bearings 13 and 14 in the frame 11 is a needle-bar and feed driving-shaft 15 having the usual balance-wheel 16 fixed to the rear end thereof. At its forward end, the shaft 15 actuates, through suitable mechanism carried in the hollow-head 12, a reciprocating needle-bar 17 which carries, at its lower end, an eye-pointed needle 18. Also carried in the hollow-head 12 is the usual spring-pressed presser-bar 19 to the lower-end of which is secured, as by a clamp-screw 20, the upright shank 21 of the hinged presser-foot 22.

Journaled in bearings 23 and 24 carried by the bed 10 is the usual rotary hook-actuating shaft 25. To the forward end of the shaft 25 is secured the usual hook element 26 which is complementary to the needle 18 in the formation of stitches. This bottom shaft 25 is driven from the top shaft 15 through the upright shaft 26 which is journaled in the bearing lugs 27 and 28 cast in the

frame 11. The top shaft 15 has fixed to it a bevel gear 29 which meshes with a bevel gear 30 fixed to the top end of the upright shaft 26. The bottom shaft 25 carries a bevel gear 31 which meshes with a bevel gear 32 fixed to the lower end of the upright shaft 26.

The top-shaft 15 carries the usual work-feeding eccentrics 33 and 34, which actuate the usual pitman rods 35 and 36 connected respectively to the rock-shafts 37 and 38. Rock-shaft 38 imparts the rising and falling movements and rock-shaft 37 imparts the feed-advance and -return movements to the feed-dog which will hereinafter be described. For a more detailed description of the present feed eccentrics and the pitman connections reference may be had to Patent No. 2,161,579, to Kaier, dated June 6, 1939.

Secured to one end of the rock-shaft 37 is a feed-rocker 39 which is rocked back-and-forth by the pitman 35. One end of a feed-bar 40, carrying a feed-dog 41 is pivotally connected to this feed-rocker 39 and its other end is formed as a fork 42 which is provided with an arcuately shaped slot 43. Slidably engaging the slot 43 are the broad bearing surfaces of a correspondingly arcuately shaped wear-block 44 which is pivotally mounted upon the pin 45 carried by the feed-lift crank 46. This feed-lift crank 46 is fixed to the rock-shaft 38 which oscillates the crank up and down and thereby imparts rising and falling movements to the feed-dog 41.

The feed-actuating eccentrics 34 and 35 are disposed relative to each other so that they are substantially 90° out of phase. This phase relation of the eccentrics will effect a timed relation between the rising-and-falling and backward-and-forward movements of the feed-bar, and consequently of the feed-dog, such as are common to so-called four-motioned feeding mechanisms.

In this type of feeding mechanism it is desirable to have the feed-dog feeding surface parallel to the sewing machine working surface while the feed-dog is in contact with the work advanced thereby. Heretofore, in sewing machines using the present type of four-motioned feeding mechanisms having the usual feed-rocker and feed-lift crank, the feed-dog begins to drop when the feed-lift eccentric has passed through its uppermost dead center position. At this time the feed-dog is moving from front to rear in its work feeding stroke. To counteract this condition in the present construction, I have provided in the feed-bar fork 42, a slot 43 having side-walls formed as the arcs of two concentric circles. As may be seen in Figs. 3 and 5, the slot 43 is curved

downwardly towards the feed-lift crank 46, and the center of curvature C of the slot 43 lies at a level below the feed-bar 40, as indicated in Fig. 5.

It is the function of the arcuately shaped slot 43 to effect an accelerated rising movement in the fork 42, relative to the feed-lift crank 46, as the feed-advance rocker 39 moves the feed-bar 40 from front to rear. It is this rising movement of the fork 42, relative to the crank 46, that compensates for the accelerated drop of the crank 46 and thus maintains a substantially parallel relation between the feeding surface of the feed-dog 41 and the machine working surface for a prolonged portion of the feed-stroke of the feed-dog 41. In the present illustrated sewing machine the working surface level is represented by the top of the throat-plate 47.

Having thus set forth the nature of the invention what I claim herein is:

1. A work-feeding mechanism for sewing machines comprising, a feed-bar, a feed-dog carried by said feed-bar, one end of said feed-bar being provided with an arcuate slot, the center of curvature of said slot lying below said feed-bar, means operatively engaging said arcuate slot for imparting rising and falling movements to said feed-dog, and means operatively connected to the other end of said feed-bar for imparting work-advancing and -return movements to said feed-dog.

2. A feeding mechanism for sewing machines comprising, a feed-bar, a feed-dog carried by said feed-bar, means operatively connected to one end of said feed-bar for imparting work-advancing and -return movements to said feed-dog, and means including a member having a bearing portion shaped as an arc of a circle slidably engaging the other end of said feed-bar for the purpose of imparting rising and falling movements to said feed-dog, the center of curvature of said arc lying at a point below the level of said feed-bar.

3. A work-feeding mechanism for sewing machines comprising, a feed-bar, a feed-dog carried by said feed-bar, a fork carried by one end

of said feed-bar and having an arcuate slot formed therein, an oscillating crank, a wear-block pivotally carried by one end of said crank and slidably engaging said arcuate slot for the purpose of imparting rising and falling movements to said feed-dog, said slot being inclined downwardly towards said oscillating crank and having its center of curvature disposed at a point below the level of said feed-bar, and means operatively connected to the other end of said feed-bar for imparting work-advancing and -return movements to said feed-dog.

4. A work-feeding mechanism for sewing machines comprising, a feed-rocker, a feed-bar having one of its ends pivoted to said feed-rocker, a feed-dog carried by said feed-bar, a fork carried by the other end of said feed-bar and having an arcuate slot formed therein, an oscillating feed-lift crank, and a block pivotally carried by one end of said crank and slidably engaging said arcuate slot, said arcuate slot being inclined downwardly towards said oscillating feed-lift crank and having its center of curvature disposed at a point below the level of said feed-bar.

5. In a sewing machine having a frame, a rotatable feed-actuating shaft journaled in said frame, a pair of eccentrics mounted upon said feed-actuating shaft and disposed substantially 90° out of phase relative to each other, a feed-rocker carried by said frame and actuated by one of said eccentrics, a feed-bar having one of its ends pivotally connected to said feed-rocker, a feed-dog carried by said feed-bar, and an oscillating feed-lift crank actuated by the other eccentric and operatively engaging the other end of said feed-bar; the improvement which consists in the provision in the feed-bar of a fork having an arcuate slot, and an arcuately shaped block pivotally carried by said feed-lift crank and slidably engaging said arcuate slot, said arcuate slot being inclined downwardly towards said feed-lift crank and having its center of curvature disposed at a point below the level of said feed-bar.
